ATTORNEY

Patented Dec. 7, 1926.

UNITED STATES PATENT OFFICE.

CECIL H. STRUPE, OF INDIANAPOLIS, INDIANA, ASSIGNOR TO LEEDY MANUFACTURING COMPANY, OF INDIANAPOLIS, INDIANA, A CORPORATION OF INDIANA.

SNARE STRAINER.

Application filed November 14, 1923. Serial No. 674,645.

The object of my invention is to produce an efficient strainer for the snares of drums, of such character that the snares may be readily associated with and dissociated from the drum head, either to produce different drum effects, with or without snares, or to permit the ready exchange of snares.

The accompanying drawings illustrate my invention.

Fig. 1 is a side elevation of a drum equipped with my improvement; Fig. 2 a side elevation, about full size, of the manipulating portion of my improved snare holder; Fig. 3 an elevation at right angles to the plane of Fig. 2; Fig. 4 a fragmentary section on line 4—4 of Fig. 3; Fig. 5 a central vertical section taken on the line 5—5 of Fig. 2; Fig. 6 a section on line 6—6 of Fig. 5; and Fig. 7 a fragmentary elevation 20 of the support for the opposite end of the snares.

In the drawings 10 indicates a main supporting bracket, adapted to be secured to the shell of the drum and most conveniently formed by a sheet metal stamping having a vertical guide slot 11 and a screw-supporting ear 12. Journalled in ear 12 is an adjusting screw 13 threaded into a post 14 which is slidably mounted in slot 11. Pivoted upon post 14 is a toggle link 15 provided with a finger piece 16 by which it may be manipulated. Pivoted to toggle link 15 is a second toggle link 17 which is also pivoted to a sliding snare-carrying plate 18, which is provided with a longitudinal slot 19 extending clear to the bottom of the plate and through which post 14 is projected. Post 14 is retained against longitudinal separation from the main support 10, by a washer 20 engaging the inner face of support 10 adjacent its slot 11. The upper end of the snare-carrying plate 18 is projected through slot 11 and provided with laterally extended ears 21 which co-operate with support 10 to retain plate 18 against lateral displacement. The lower end of plate 18 is turned inwardly and perforated at 22, in the usual manner, to receive the snares 23.

Link 17 is shouldered at an intermediate point as indicated in Figs. 2, 4 and 5, so as to limit the throw of link 15 relative thereto, to the two extremes shown in Figs. 2 and 4 respectively, the construction being such that, when the parts are in the position shown in Fig. 4, the toggle is "broken" to one side of

its neutral sufficiently to permit the tension 55 of the snares to retain the parts in that position.

With the parts in the position shown in Figs. 1 and 4, the snares are strained against the head of the drum 25 and the desired tension is obtained by an adjustment of the post 14 in slot 11 by means of screw 13. By pressing downwardly on the outer end of finger piece 16 the toggle 15—17 is "broken" in the opposite direction so that the parts may 60 move to the position shown in Figs. 2 and 3 thus permitting the snares to drop away from the head of the drum. The snares may be immediately returned to head-engaging position by a movement of finger piece 16 70 to the position shown in Fig. 4.

To remove the snares from the drum, screw 13 is turned enough to separate post 14 therefrom, whereupon the post and the snare-carrying plate and other parts associated therewith may be withdrawn from the support 10, and the snares removed from the drum, the opposite ends of said snares being conveniently carried by a support 30 secured 80 to the shell of the drum.

I claim as my invention:

1. A snare strainer comprising a supporting bracket, a snare engaging plate slidably mounted on said bracket, an abutment post slidably associated both with the bracket and the plate, a connection between said post and bracket by means of which the post may be adjusted relative to the bracket, and a connection between the post and snare-engaging plate by which said plate may be 90 quickly shifted relative to the post and bracket.

2. A snare strainer comprising a supporting bracket, a snare engaging plate slidably mounted on said bracket, an abutment post 95 slidably associated both with the bracket and the plate, a connection between said post and bracket by means of which the post may be adjusted relative to the bracket, and a toggle connecting said post and snare engaging 100 plate and provided with a manipulating finger piece.

3. A snare strainer comprising a main bracket longitudinally slotted by a slot open at one end, an abutment post slidably mounted in said slot and extractable from the open end thereof, an adjusting screw separably connecting said bracket and post, a

- snare-carrying plate slidably associated both with the bracket and the post, and means connecting said post and plate by which the plate may be quickly shifted relative to the post.
4. A snare strainer comprising a main bracket longitudinally slotted, an abutment post slidably mounted in said slot, an adjusting screw connecting said bracket and post, a snare carrying plate slidably associated both with the bracket and the post, and means connecting said post and plate by which the plate may be quickly shifted relative to the post.
- 10 5. A snare strainer comprising a slotted bracket, an adjusting screw journaled in said bracket parallel with the slot, a snare plate slidably mounted on the bracket and interlocking with the slot, a nut threaded to receive the adjusting screw and having a shank projected through a slot in the snare plate and the slot in the bracket and axially interlocked with the bracket, a toggle link journaled on said shank, a second toggle link journaled on the snare plate and pivotally connected to the first toggle link, and a

finger piece carried by one of said toggle links.

6. A snare strainer comprising a main bracket longitudinally slotted by a slot open at one end, an abutment post slidably mounted in said slot and extractable from the open end thereof, an adjusting screw separably connecting said bracket and post, a snare-carrying plate slidably associated with the bracket and post, and a toggle connecting the post and plate, and provided with a manipulating portion.

7. A snare strainer comprising a main bracket longitudinally slotted, an abutment post slidably mounted in said slot, an adjusting screw connecting said bracket and post, a snare-carrying plate slidably associated with the bracket and post, and a toggle connecting the post and plate, and provided with a manipulating portion.

In witness whereof, I, CECIL H. STRUPE, have hereunto set my hand at Indianapolis, Indiana, this 9th day of November, A. D., one thousand nine hundred and twenty- three.

CECIL H. STRUPE.
